UNITED STATES PATENT OFFICE.

MARIE LOUISE FULLER, OF NEW YORK, N. Y.

DESIGN FOR A DANCING-DRESS.

SPECIFICATION forming part of Design No. 21,458, dated April 12, 1892.

Application filed March 7, 1892. Serial No. 424,087. Term of patent 7 years.

To all whom it may concern:

Be it known that I, MARIE LOUISE FULLER, a citizen of the United States, residing at New York, in the county and State of New York, have invented and produced a new and original Design for Dancing-Dresses, of which the following is a specification, reference being had to the accompanying drawing, forming part thereof.

This design has for its object to provide a novel and ornamental dancing-dress, and the leading feature thereof resides in a dress-skirt having sinuous representations thereupon.

The design is illustrated by the accompanying drawing, in which the figure is an elevation of a dancing-dress illustrating my design.

In the drawing, the letter A indicates the skirt of the dancing-dress, which is provided with a sinuous representation, such as a ser-

pent B, placed in proximity to the border of the skirt, and above the sinuous representation B is also arranged several sinuous representations C.

The design provides a novel and ornamental dancing-dress which presents a distinguishing and characteristic appearance to the eye. The sinuous representations are shown as provided with eyes F and forked tongues G. The waist H of the dress is provided with sinuous representations I.

What I claim is—

The design for a dancing-dress, substantially as shown and described.

In testimony whereof I have hereunto set my hand in the presence of two subscribing witnesses.

MARIE LOUISE FULLER.

Witnesses:

ISAAC N. FALK,
WM. C. HAUFF.
